DEVICE FOR CLEANING BOBBINS

Edgar Alexander McKillop, Hendersonville, N. C.

Application November 5, 1931, Serial No. 573,273
Renewed October 27, 1933

PUBLISHED

1 Claim. (Cl. 15—20)

This invention relates to a device for cleaning the central passages in bobbins. Machines have been employed known as bobbin strippers in which the bobbins are placed periodically in a predetermined position and lint which collects upon the exterior of the quill or bobbin is blown or brushed off. The clean bobbins are then removed and are ready for use. These machines automatically place the quills in the cleaning position and also remove them periodically from such position. The axial passages of the bobbin, however, are cleaned manually by means of tools or wires which are passed through the central core.

An object of the invention is the provision of a device for automatically cleaning the axial passages of quills or bobbins by forcing compressed air through the passages with the quills being placed in operative position for the axial cleaning and then removed to permit successive quills to be placed in position to receive a blast of compressed air.

Another object of the invention is the provision of a device for forcing compressed air through the axial passage of a quill or bobbin for removing lint collected therein in which a nozzle is moved into snug contact with the smaller end of the quill and in alignment with the axial passage so that when the carrier carrying the nozzle is reciprocated and the nozzle is in contact with the quill a valve will be automatically operated for forcing a blast of compressed air through the nozzle and through the axial passage of the quill.

A further object of the invention is the provision of a device for cleaning the axial passages of the quills or bobbins in which a nozzle is moved into contacting relation with one end of the quill, the nozzle being carried by a carriage which is periodically reciprocated towards and away from the quill while the quill is held temporarily in a fixed position for the cleaning operation.

This invention will be best understood from a consideration of the following detailed description, in view of the accompanying drawings forming a part of the specification; nevertheless, it is to be understood that the invention is not confined to the disclosure, being susceptible of such changes and modifications which shall define no material departure from the salient features of the invention as expressed in the appended claim.

In the drawings:

Figure 1 is a plan view partly in section of a

device constructed in accordance with the principles of my invention.

Figure 2 is a side elevation of the device which parts in section.

Figure 3 is a vertical section of the oscillating means for the movable carriage, and

Figure 4 is an enlarged section of the air nozzle.

Referring more particularly to the drawings, 10 designates a bracket to which is secured an arm 11 by means of screws 12. This arm is formed integrally with a casing 13 which provides a housing for a rock shaft 14. The bracket 10 forms part of an Utsman bobbin stripper or other similar machine which is adapted to clean the exterior walls of the quills or bobbins, the last-named device containing means for automatically 30 positioning the quills or bobbins for cleaning purposes but since this stripper forms no part of the present invention, the same is not shown.

An operating shaft of the stripper indicated 75 at 15 and a coupling sleeve 16 connects the shaft 15 with a shaft 17, set screws 18 being employed for connecting the sleeve 16 to the respective shafts. The shaft 15 is rocked through an angle of approximately 10° to 15° as is likewise the shaft 17 for a purpose which will be presently explained.

The housing 13 has an upper extension 20 with its opposite ends open to receive bearings 21 and 22 which are secured in place by means of bolts 23.

A boss 24 is formed on the top of the extension 20 of the casing 13 and is provided with a threaded passage receiving a plug 25. The passage in which the plug 25 is threaded provides 90 means for the application of a lubricant to the working parts within the casing 13.

The shaft 17 is provided with an enlarged portion 26 having a spiral groove 27 which receives a tooth 28 formed radially on the shaft 14.

A bar 30 passes through an opening in the shaft 14 and is secured in place on said shaft by means of a set screw 31. The shaft has an offset portion 32 which is received within a sleeve 33 having ears 34 which are secured to the outer end 100 35 of a slidably mounted carriage 36 by means of bolts 37. The opposite end of the bar 30 is provided with a sleeve 40 to which is connected one end of a coil spring 41. The other end of the coil spring is secured to a rod 42 which in 105 turn is attached to one end of the casing 13. The spring 41 is adapted to maintain the bar 30 in a predetermined position which is substantially at right angles to the shaft 17.

The bracket 10 of the bobbin stripper referred 110

to above is provided with a channel member 45 in which is mounted a housing 46. This housing includes a base member 47 and side walls 48. The side walls of the housing are sheared off, as shown at 49, at an angle to the vertical and this housing receives the carriage 36.

The carriage consists of a base member 50 having a vertically disposed end member 51 formed integrally with the base member and provided with an opening to receive a pipe 52. A block 53 which is secured to the member 51 is also provided with an opening to receive the pipe 52. A set screw 54 secures the pipe to said block. A support 55 has a foot 56 which is secured to the base member of the carriage 36. This member 55 is provided with an opening which receives the pipe 52 so that the block 53 and members 51 and 55 support the pipe 52 upon the carriage 36.

20 A nozzle, generally designated by the numeral 60, is secured to the end of the pipe 52 which projects beyond the member 51. The nozzle consists of a sleeve 61 threaded at 62 upon the outer end of the pipe 52. This sleeve has a countersunk portion which is threaded as shown at 63 to receive an internal sleeve 64. A head 65 is threaded at 66 upon the internal sleeve 64 for securing the head 65 to the sleeve 61 and likewise to the pipe 52.

30 The head 65 is provided with a lip portion 67 projecting outwardly from the head 65 at the lower end to receive the reduced end 68 of a quill or bobbin 69. This construction permits the quills to be placed in contact with the nozzle so that the axial passage 70 of the quill 69 will be aligned with an axial passage 71 in a rubber sleeve 72. This sleeve is forced into the sleeve 64 and is provided with a shoulder 73 engaging a complementarily-constructed shoulder formed interiorly of the head 65.

40 A supporting member for the quill 69 is shown at 75 and this member consists of similarly constructed members and similarly constructed plates 76 which has a lower inner offset portion 77 perforated to receive a bar 78. The bar 78 is received by the side walls of the chute or channel member 45. The upper end of the plates 76 are spaced apart sufficiently to snugly receive an intermediate portion of a quill 69.

50 A second support is shown at 80 in the form of an arm extending towards the nozzle 60. This arm is provided with a slot 81. A block 82 rises from the outer free end 83 of the arm 80 and is provided with a vertical passage 84 in alignment with the central passage 70 of the quill 69 to permit lint, as shown at 85, to pass downwardly after the said lint has been blown from the axial passage of the quill. The outer free ends of the block, as shown at 86, are adapted 60 to engage the outer enlarged end 87 of the quill 69 for aiding in supporting the quill when the smaller end of the quill is in engagement with the nozzle 60.

65 A rod 90 is secured at 91 to a bracket arm 92 depending from the channel member 45. At the outer end of the arm, as shown at 93, is pivotally mounted one end of a lever 94 which is bent intermediate its ends, as shown at 95, to provide an offset arm 96. This arm is pivoted at 97, 70 upon ears 98, depending from a cuff 99. The lever 94 is provided with a seat 100 for a purpose which will be presently explained.

75 A valve casing, as shown at 101, is provided with a valve 101^a having a depending stem 102 which is adapted to be in engagement with the

seat 100 on the lever 94. A spring 102^a maintains the valve closed. The casing 101 is in communication with the pipe 52 and with a pipe 103 which is connected with a flexible tubing 104. This tubing is connected with a source of compressed air.

The operation of my device is as follows: The device for cleaning the axial passages of quills or bobbins is used in connection with a stripping machine which is adapted to automatically place the quills or bobbins in a predetermined position for stripping the lint from the exterior walls of the quills or bobbins and for removing the lint after the cleaning operation has been completed. While these quills or bobbins are being held in place for the stripping operation the nozzle 60 has time to move into snug contact with the reduced end of the tapered bobbin or quill 69 by the mechanism shown in Fig. 3 and as the carriage 36 is moved towards the reduced end of the bobbin the lever 94 is actuated so that when the rubber sleeve 72 has come into snug engagement with the end of the quill 69, the lever 94 will be tilted sufficiently to elevate the stem 102 and thereby open the valve within the housing 101 so that a blast of compressed air will be forced through the axial passage 70 of the quill 69 and force the lint from the enlarged end 87 as shown at 85 in Fig. 2. The carriage is then moved in the opposite direction, releasing the quill 69 so that the mechanism (not shown) will be permitted to remove the quill and place another quill in position for the cleaning of the lint from the axial passage of said quill.

It will be seen that since the shaft 17 is rocked through a small angle by the shaft 15, the spiral groove 27, receiving the tooth 28 of the shaft 14, will cause the shaft 14 likewise to be rocked, thereby oscillating the rod 30 so that the offset portion 32 of the rod 30 will be moved outwardly 115 and thus move the carriage 36 in the same direction and the nozzle 60 away from the reduced end of the quill 69. As the shaft 15 is rocked in the opposite direction and likewise the shaft 17, the shaft 14 will be moved in the opposite 120 direction, thereby rocking the rod 30 so that the offset portion 32 will move the carriage inwardly to cause the nozzle 60 to engage a successive quill.

The rocking of the lever 94 is again repeated for opening the valve within the casing 101 to 125 permit a further blast of compressed air into the newly positioned quill.

When the carriage 36 is moved in the opposite direction the arm 94 is rocked outwardly, thereby lowering the seat 100, thereby closing the 130 valve in the casing 101.

A rod 110 is secured to the side walls 48 of the housing 46 and in close association with the bottom of the carriage 36 so that the carriage will be maintained in position within its respective 135 housing during the reciprocating movement of the carriage. The rocking of the shaft 30 is through an arc of approximately 10° to 15° and the movement of the member 52 is not over five-sixteenths of an inch, so that while the lever 94 140 is pivotally connected at one end with the rod 90 and at its other end with the ears 98, of the sleeve 99, the rod 90 may be flexed slightly during the very limited travel of the member 52.

I claim:

145 A bobbin cleaner comprising an air nozzle, means for supporting a bobbin with the hollow interior of the bobbin aligned with the discharge opening of said nozzle, means for reciprocating the nozzle and for moving said nozzle 150

temporarily into snug engagement with one end of the bobbin, a pipe connecting the nozzle with a source of air and reciprocated with the nozzle, a valve incorporated in the pipe for controlling the flow of air to the nozzle, said valve having a stem, a rod having one end secured to a fixed support, a lever having one end pivoted to the free end of the rod so that the lever may be oscillated from the free end of the rod, the other end

of the lever being pivotally connected to the pipe, the lever having a projection engageable with the stem, so that when the lever is oscillated in one direction by the reciprocation of the nozzle, the projection will move the valve to open position.
